UNITED STATES PATENT OFFICE.

JOHN ARTHUR FEATHER, OF NEW BEDFORD, MASSACHUSETTS, ASSIGNOR TO POWDRELL & ALEXANDER, INC., OF BOSTON, MASSACHUSETTS, A CORPORATION OF MASSACHUSETTS.

DESIGN FOR A TEXTILE FABRIC.

Application filed August 21, 1926. Serial No. 18,797. Term of patent 7 years.

To all whom it may concern:

Be it known that I, JOHN ARTHUR FEATHER, a citizen of the United States of America, residing in New Bedford, in the county of Bristol and Commonwealth of Massachusetts, have invented a new, original, and ornamental Design for a Textile Fabric, of which the following is a specification, reference being had to the accompanying drawing, forming part thereof.

The figure is a face view of the fabric.

I claim:

The ornamental design for a textile fabric as shown.

Signed by me at New Bedford, in the county of Bristol, and Commonwealth of Massachusetts, this ninth day of August, 1926.

JOHN ARTHUR FEATHER.
